UNITED STATES PATENT OFFICE.

ALFRED WARNE, OF MIAMI, FLORIDA.

FOLDING TRUNK.

1,114,321.

Specification of Letters Patent.

Patented Oct. 20, 1914.

Application filed March 31, 1913. Serial No. 758,078.

To all whom it may concern:

Be it known that I, ALFRED WARNE, citizen of the United States, residing at Miami, in the county of Dade and State of Florida, have invented certain new and useful Improvements in Folding Trunks, of which the following is a specification.

This invention relates to an improvement in trunks.

10 The primary object of the invention is to provide a trunk which, when not in use, may be collapsed to occupy a comparatively small space.

15 A further object of the invention is to so construct the sections of which the trunk is formed that it may be readily taken apart and the sections assembled in a compact package which may be conveniently transported or which, when stored, will occupy 20 but little space.

A still further object of the invention is to provide connecting means for the sections which will not be affected by handling the trunk.

25 A still further object of the invention is to provide connecting means for the side and end sections which will be maintained against accidental displacement by the weight of the trunk tray, the connecting 30 means forming a support for the tray.

For a full understanding of the invention, reference is to be had to the following description and accompanying drawings, in which:—

35 Figure 1 is a perspective view of the trunk, the lid being raised; Fig. 2 is a perspective view with the lid closed; Fig. 3 is a perspective view, the front wall and the tray being removed; Fig. 4 is a longitudinal 40 section; Fig. 5 is a perspective view of the trunk in its folded position; Fig. 6 is a transverse section of the trunk folded; Fig. 7 is a detail view of the connecting means for the side and end sections; and Fig. 8 is a detail view showing the manner in which 45 the tray prevents the displacement of the pintle pins of the hinge members which are secured to the wall of the trunk.

Corresponding and like parts are referred 50 to in the following description and indicated in all the views of the drawings by the same reference characters.

Broadly, the present invention contemplates the provision of a trunk formed of 55 sections which may be disassembled, certain of the sections after being disassembled

forming a pocket or receiving member in which the other sections may be placed, the strap fastening means of the trunk being so arranged that it may be used to securely hold the sections together. 60

In the drawings, 10 designates the bottom of the trunk. The end walls 11 are hingedly connected to the edges 12 of the bottom, the hinges 13 being secured to the inner faces of the bottom and end walls. The side members 14 and 15 are the same height as the end walls 11. These side members are hingedly connected to the end walls, the hinge connection being illustrated in detail in Fig. 7. This hinge connection consists of the hinge plates 17 disposed in pairs with their pintle lugs interlocking in the usual manner. There are four sets of these connections provided, one set being arranged at 75 each corner of the trunk.

Each set of hinge plates is connected by a rod 18. The upper terminals of the rods 18 are formed with an extension 19 which is provided with a flat face on which the trunk tray 20 rests. It will thus be noted that the tray 20 is supported at each corner of the trunk, the tray maintaining the rods 18 within the pintle lugs, the tray holding the rods 18 against accidental displacement. 80 The tray is also supported by strips 21 secured to the inner faces of the end walls 11. It will be seen by this construction, that the side and end walls are hingedly connected, and that the side walls may be removed 90 from the end walls by lifting the rods 18 out of the pintle lugs of the hinge plates 17.

A strip 22 is hingedly connected to the side section 14, which forms the rear wall of the trunk, each pair of hinge plates 23 having their pintle lugs connected by a pin 24 which may be conveniently removed to separate the section 14 from the strip 22. These pintle pins are supported against displacement by lugs 25 arranged on the rear wall 100 of the tray.

The top section or lid 26 of the trunk is hingedly connected to the strip 22. This top section is provided with the end members 27 and the side member 28 which form a continuation of the end and side sections when the lid is closed. 105

The tray 20 consists of the bottom board 29 to which the longitudinal members 30 are hingedly connected, whereby they may 110 fold upon the bottom board. The inner faces of the longitudinal members 30 are

formed adjacent each end and at a point intermediate their ends with guide ways 31 which receive the terminals of the partitioning members 32. These partitioning members 5 are inserted within the guide ways, thereby maintaining the longitudinal members 30 at right angles to the bottom board 29. By this construction, it will be noted that the tray may be collapsed by removing 10 the partitioning members and folding the longitudinal members 30 on the bottom board.

Straps 33 are secured to one edge of the bottom 10, said straps being provided with 15 buckles which receive the straps 34 which are secured to the other edge of the bottom. These straps embrace the trunk when the same is set up for use.

When it is desired to collapse the trunk, 20 the tray is removed and the partitioning members withdrawn from the guide ways 31, in order that the longitudinal members 30 may be folded upon the bottom member 29, the partitioning members 32 being placed 25 upon the board with their end portions disposed beneath the longitudinal members 30. The pins 18 are then removed and the end sections 11 folded upon the bottom 10, the bottom being formed with recesses 35 which 30 receive the tray supports 21 in order that the end sections, when folded, may be disposed flush with the bottom.

When the side section 14, which forms the rear wall of the trunk, is removed, the pintle pins that connect the hinge plates 23 35 are withdrawn, separating the section 14 from the strip 22. The side sections 14 and 15 are then placed together, their faces which carry the hinge plates contacting with 40 each other, the pintle lugs of all the plates 17 of one section being brought into interlocking relation with the pintle lugs of the plates 17 of the other section. The rods 18 are then inserted, securely locking the side 45 sections together. The strip 22 is swung upon its hinge until its end portions 36 contact with the edges 37 of the end members 27 of the top, thus forming a rectangular receptacle. The tray in its collapsed form 50 is placed within the receptacle thus formed, and the side sections 14 and 15, which are locked together, are placed upon the tray. The bottom section, to which is hingedly connected the end walls 11, is then placed 55 upon the side sections 14 and 15. The side and end sections 27 and 28 of the top section or lid 26 are provided with an extension 38 which, when the sections are thus assembled, embraces the edge of the bottom 10, 60 forming a compact, substantially rectangular package which occupies comparatively little space and which may be conveniently transported. It will be obvious that with the sections assembled as described above, 65 the straps 33 and 34 may be connected and

the sections effectually held together. The sections are so arranged within the rectangular receptacle formed by the lid that relative movement of the same is prevented.

Particular attention is called to the simplicity of the connecting means, and to the fact that the sections may be conveniently disassembled without the use of cumbersome spring catches and locks. It will also be seen that the entire structure may be easily 75 and economically manufactured, and that the connecting means for the sections occupies comparatively small space within the trunk, said connecting means being so disposed that clothing which is placed within the trunk will not be torn through contact with the same. Attention is also called to the manner in which the side and end sections are connected, and to the fact that the 80 tray forms a locking means for this connection. It will be noted that when the trunk is set up for use, it is as substantial as the usual form of trunk, and handling of the trunk cannot displace the connecting means or in any way endanger the trunk being partially collapsed when in use, the sections being so connected as to coact with each other to form a substantial structure.

Having thus described my invention, what I claim as new and desire to secure by Letters Patent is:

1. A trunk including a bottom, end sections hingedly connected to the bottom, side sections, a connection between the side and end sections, said connection comprising interlocking plates, the plates of one side section being disposed to interlock with the plates of the other side section when the sections are disassembled, a strip hingedly connected to one of the side sections, and a lid hingedly supported by the strip, said lid and strip forming a substantially rectangular receptacle when the sections are disassembled.

2. A trunk including a bottom, end sections hingedly connected to the bottom, side sections, hinge plates carried by the side and end sections, said hinge plates being formed with pintle lugs, the pintle lugs of the hinge plates of the end sections interlocking with the pintle lugs of the hinge plates of the side sections, and a tray support consisting of a rod disposed to extend through the interlocking pintle lugs of the hinge plates and secure the side and end sections together, said rod being formed with a flattened terminal disposed at right angles to its body portion on which the tray of the trunk is adapted to rest.

3. A trunk including a bottom, end sections hingedly connected to the bottom, side sections, a connection between the side and end sections, said connection comprising interlocking plates, a member constituting a tray support disposed to maintain said

plates in interlocking engagement, the plates of one side section being disposed to interlock with the plates of the other side section when the sections are disassembled.

- 5 4. A trunk including a bottom, end sections hingedly connected to the bottom and disposed to fold thereon when the trunk is disassembled, side sections, the side and end sections each carrying plates formed with 10 pintle lugs, the pintle lugs of the plates carried by the side members interlocking with the pintle lugs of the plates carried by the end members, means constituting a tray support for securing the interlocking pintle

lugs together, a strip hingedly connected to 15 one of the side sections, a lid hingedly connected to said strip, said lid being formed with side and end sections which coact with the strip to which the lid is hinged to form a rectangular receptacle for the side and 20 end sections of the trunk, the bottom of the trunk constituting a lid for said receptacle.

In testimony whereof I affix my signature in presence of two witnesses.

ALFRED WARNE. [L.S.]
